UNITED STATES PATENT OFFICE

157,503

CARD READER FOR A COMPUTING MACHINE

George H. Kress, Vestal, N. Y., and Carl W. Sundberg, Detroit, Mich., assignors to International Business Machines Corporation, New York, N. Y., a corporation of New York

Application June 16, 1948, Serial No. 146,994

Term of patent 14 years

(Cl. D64—11)

To all whom it may concern:

Be it known that we, George H. Kress and Carl W. Sundberg, both citizens of the United States of America, residing, respectively, at Vestal, in the county of Broome and State of New York, and at Detroit, in the county of Wayne and State of Michigan, have invented a new, original, and ornamental Design for a Card Reader for a Computing Machine, of which the following is a specification, reference being had to the accompanying drawing, forming part thereof.

Figs. 1, 2 and 3, are, respectively, a perspective view, a front elevation and a right end elevation of a card reader for a computing machine showing our new design.

We claim:

The ornamental design for a card reader for a computing machine, as shown.

GEORGE H. KRESS.
CARL W. SUNDBERG.
